WASHING MACHINE

Carl J. Soderholm, Minneapolis, Minn.

Application November 14, 1935, Serial No. 49,741

11 Claims. (Cl. 259—95)

This invention relates to washing machines.

Heretofore numerous washing machines have been developed of the injected water stream type, i. e. where the water action is accomplished in a tub without the use of moving parts in the tub and solely by injecting a stream or streams of water within the tub. Such machines have met with but limited commercial success by reason of the fact that the washing fluid, containing soap, will foam excessively and no successful provision has been made to prevent cumulative foaming action.

It is one of the main objects of the present invention to provide a novel and improved washing machine of the injected water stream type wherein excess foaming of the washing fluid is prevented.

To these ends, generally stated, the invention consists in the novel parts and novel combinations of parts and in the novel processes and the novel steps in the processes hereinafter defined in the claims, and described in the following specification, made in connection with the accompanying drawing; wherein like reference characters refer to the same or similar parts throughout the various views, and, in which,

Fig. 1 is a central vertical section taken through a washing machine embodying the invention on the line 1—1 of Fig. 2, as indicated by the arrows;

Fig. 2 is a vertical section taken on the line 2—2 of Fig. 1, as indicated by the arrows; and

Fig. 3 is a plan of the tub of the machine.

For ease of description in the specification and claims, the front of the machine is considered to be the left hand portion of the machine, as shown in Fig. 1, of the drawing.

Referring to the drawing, there is provided, in accordance with the form illustrated, a tub designated as an entirety by the letter A. This tub can probably best be described as having the general shape of the bowl of an ordinary Irishman's clay smoking pipe. In plan view the tub A is of general circular shape; in transverse vertical section, as shown in Fig. 2, the tub is of general semi-circular shape; and in central longitudinal vertical section as shown in Fig. 1, the tub is of somewhat forwardly tipped funnel shape. The back 4 of the tub is for the most part vertically disposed, curving into the sides 5 and also curving into the bottom 6. The bottom 6, while being dished and curving into the sides 5, inclines generally upwardly and forwardly from the back 4 to merge into the upwardly curved front 7. Set normal to the upper part

of the front 7 and projecting rearwardly therefrom is a top section forming a water deflector 8. The upper parts of the sides 5 and the back 4 are quite sharply inwardly curved adjacent the level of the deflector 8 to form the continuously inwardly curved upper section 9. A multiplicity of circumferentially spaced drain apertures 10 are provided in the curved upper section 9 and in the form shown rows of these apertures are provided at three different levels, the two lower rows being at levels adjacent but spaced somewhat below the level of the deflector 8 and the upper row of apertures being about at the same level as the deflector 8. A short continuous flange rises from the inner edges of deflector 8 and the curved upper section 9 form a neck 11.

In the form illustrated the tub A is received within a reservoir 12 having the same general contour as to its back, bottom, sides and front, as these same parts of the tub A but being of somewhat larger size than the tub A. This reservoir 12 may be provided with a skirt 13 about its sides and front as shown to give it a somewhat better appearance. The tub A disposed in inwardly spaced relation from reservoir 12 may be conveniently supported from the bottom of the reservoir by means of rubber capped lugs 14 attached to the bottom of the reservoir, the rubber caps 14a being provided to stabilize the tub A and to prevent the transmission of vibrations from the tub A to the reservoir 12. It is, of course, understood that the rubber capped lugs 14 are not directly connected to the tub A so that it is possible to readily remove the tub from the reservoir for cleaning of the reservoir or the like.

The reservoir 12 is equipped with suitable downwardly extending legs 15 whereby the entire machine may be supported as upon a floor or the like. The upper edge of the reservoir, which is circular in shape, projects somewhat above the neck 11 and received over the top of the reservoir is a closure plate 16. Plate 16 has an outer down turned flange received about the outer part of the upper portion of the reservoir 12 and it has a down turned inner flange received within the neck 11. To permit ready drainage of water that may accumulate on the closure plate 16, the plate inclines somewhat downwardly from its outer to its inner portion. A shouldered and flanged cover 17 carrying a handle is received within the inner flange of the closure plate 16 to close the top opening in the tub A.

Secured to a shelf 18 attached to the rear

55

legs 15 is an electric motor 19 driving through its shaft 20 a water pump 21 also mounted on the shelf 18. Water pump 21 has its intake 21a connected to the lowest part of the reservoir 12 at the central rear portion of the bottom of the reservoir. The outlet 21b of pump 21 runs through and is connected to the back of the reservoir and it extends through an opening in the back 4 of the tub A at the central lower part of the same. The outlet 21b terminates in a mouth 21c directed forwardly within tub A in slightly spaced relation above the bottom 6 of the tub. Pump 21 is equipped with a drain cock 22 connected to its lowermost portion. 5

15 In preparing the washing machine for operation the tub A and the reservoir 12 are filled to a point somewhat below the level of the lowermost apertures 10. Of course, the cover 17 is removed to fill the machine and the water together with whatever soap or other washing compounds are to be used are initially placed within the tub A, the water working its way through pump 21 until part of it is received within reservoir 12. The clothes to be washed 20 may then be introduced whereupon the top opening in the tub is closed by the cover 17, and the motor 19 is set in operation to drive the pump 21. The pump 21 will draw the washing fluid from the bottom of the reservoir 12 and 25 force the same violently into the tub A through the mouth 21c. Almost immediately the height of the washing fluid within the tub A will rise to a point above the lowermost apertures 10 while of course the level of the fluid within the reservoir 12 will drop to a point considerably 30 below the lowermost apertures 10.

35

The stream of washing fluid injected into the tub A will move rapidly upwardly and forwardly from the back 4 of the tub along the bottom 6 and along the front 7, whereupon it will strike the deflector 8 and be directed rearwardly as indicated by the arrows, Fig. 1. Water will drain into the reservoir 12 through the various apertures 10 and due to the fact 40 that the apertures are circumferentially spaced from each other through an arc of at least 120° and preferably through a longer arc, the drainage of the washing fluid through these different apertures will not exert sufficient pull on the clothes within the tub to cause the clothes to 45 lodge against the apertures, clog the same and prevent free circulation of the clothes. As the stream of water injected into the tub from the pump strikes the washing fluid already in the 50 tub and the clothes within the tub, all the washing fluid in the tub, together with the clothes, will be given a circulatory movement revolving generally roughly about a cylindrical axis horizontally disposed transversely in the center 55 of the tub. The clothes having moved upwardly and forwardly along the bottom 6 and front 7 and having been deflected rearwardly by the deflector 8 will arrive at the rear upper portion of the tub, whereupon the weight of the 60 water soaked clothes will tend to cause them to sink by gravity to the bottom of the tub to be again acted upon by the stream ejected from the pump. Of course, the general current movement of the fluid in the tub will also assist 65 in causing the recirculation of the clothes to the bottom of the tub.

70

By reason of the circulatory action of the clothes, the clothes will string out in a more or less sheet-like form and will not knot, tie or 75 tangle together. Due to the fact that the main

body of fluid within the tub moves at a slower speed than the high velocity stream injected into the tub from the pump, the high velocity stream works through the clothes to produce a thorough cleansing action. Also the clothes move more rapidly near the front of the tub than at the rear portion of the tub which produces a further differential in the water action on the clothes, further assisting in the washing action. The weight of the clothes at the rear 10 part of the tub tends to cause them to drop somewhat more rapidly from the rear part of the tub to the bottom of the rear tub at this point, thereby producing a further differential 15 between the speed of movement of the clothes and the speed of movement of the water to assist the washing action. By reason of these facts, the clothes are very rapidly washed and very thoroughly washed.

As the machine is put into action, the agitation of the washing fluid containing soap causes suds to form in the tub, these suds rising to the top of the tub. If nothing was done to prevent the cumulative formation of these suds at the top of the tub, the suds would soon form so 25 much foam as to interfere with the action of the machine. The apertured curved section 9 at the upper part of the tub prevents the cumulative formation of this sudsy foam. The foam will, of course, form until it rises to a level 30 above the lowermost apertures 10 and usually to a point about level with the middle row of apertures 10. The formed foam moved by the water at the top of the tub is carried over to points adjacent the various apertures 10 and 35 the water draining through these apertures operating with the curvature of the curved section 9 causes the foam to drain out of the tub particularly through the higher apertures into 40 the reservoir 12. The curved section 9 in conjunction with the surface of the water in the tub and the movement of the water towards the apertures traps the foam so as to cause its ejection from the tub. This same action does not 45 take place when the curved section 9 is not provided in the tub. The prevention of the cumulative formation of sudsy foam at the top of the tub is one of the most important features 50 of the present invention. The location of the curved section 9 at approximately the same level as the deflector plate 8 also seems to have something to do with the elimination of the foam 55 from the tub.

The water draining down from the apertures 10 in the reservoir 12 produces a water falls 55 action to prevent the cumulative formation of foam in the reservoir. In other words, the water draining from apertures 10 keeps washing the sudsy foam down in the reservoir so as to mix the foam with the water and destroy the foam. 60

To drain the machine it is only necessary to open the cock 22 in the pump. The outlet 21b of the pump fits loosely through the opening in the rear of the tub A so that when desired, cover 17, closure plate 16 and the tub A can be 65 quickly removed from the reservoir 12.

The fact that there are no moving parts within the tub A, prevents wear on the clothes while they are being washed. The tearing of the clothes and the breaking of buttons thereon 70 is held to the minimum.

It will, of course, be understood that various changes may be made in the form, details, arrangement and proportions of the machine of the present invention and the changes may be 75

made in details of the washing process without departing from the scope of the present invention which, generally stated, consists in the matter shown and described and set forth in the appended claims.

5 The present application contains certain subject matter which is common to my prior application entitled "Washing process and machine", Serial Number 747,035, filed October 5, 1934, 10 and accordingly the present application is a continuation in part of my said prior application.

What is claimed is:

1. In a washing machine, a tub having a rearwardly extending deflector joining the upper portion of its front and having the upper portion of the remainder of the tub inwardly curved adjacent the level of said deflector, the inwardly curved portion having a multiplicity of horizontally spaced drain apertures therein, certain of 20 which are located at different levels, means for circulating washing fluid upwardly along the front of the tub to strike said deflector and means for catching the fluid draining through said apertures and supplying said circulating 25 means with the drained washing fluid.

2. In a washing machine, a tub having a substantially circular upper portion in plan view, a rearwardly extending deflector joining the upper portion of the front of the tub, the remainder 30 portion of the upper portion of the tub other than the front thereof having a continuous inwardly curved section at a level approximately flush with said deflector, said curved section having a multiplicity of drain apertures therein located 35 at horizontally spaced points extending through an arc of at least 120°, certain of said apertures being located at different levels, means for circulating washing fluid upwardly along the front of the tub to strike said deflector and means 40 for catching the washing fluid draining through said apertures and supplying said circulating means with the washing fluid.

3. A washing machine comprising a tub having a bottom inclining upwardly and forwardly 45 from the rear of the tub, the upper part of the front of the tub having a rearwardly extending water deflector joining the same and the upper part of the remainder of the tub being inwardly curved adjacent the level of said deflector and the curved portion having a multiplicity of circumferentially spaced drain apertures therein located certain of them at different levels close to but somewhat below the 50 level of said deflector, a reservoir surrounding at least a portion of said tub and receiving from said drain apertures, a water pump receiving from said reservoir and having a forwardly directed discharge mouth discharging into said tub at the rear lower part of the same and means 55 for operating said pump.

4. A washing machine comprising a tub having a bottom inclining upwardly and forwardly from the rear of the tub, the upper part of the front of the tub having a rearwardly extending water 60 deflector joining the same and the upper part of the remainder of the tub being inwardly curved adjacent the level of said deflector and the curved portion having a multiplicity of drain apertures therein circumferentially spaced 65 through at least 120° of a circle and located certain of them at different levels close to but somewhat below the level of said deflector, a reservoir receiving from said drain apertures, a water pump receiving from said reservoir and

having a forwardly directed discharge mouth discharging into said tub at the rear lower part of the same and means for operating said pump.

5. A washing machine comprising a tub having a bottom inclining upwardly and forwardly 5 from the rear of the tub, a horizontal deflector set substantially normal to the upper edge of the front of the tub and projecting rearwardly therefrom, said deflector joining the upper part 10 of the front of the tub and the upper part of the remainder of the tub being inwardly curved adjacent the level of said deflector and the curved portion having a multiplicity of circumferentially spaced drain apertures therein located certain of them at different levels close 15 to but somewhat below the level of said deflector, a reservoir receiving from said drain apertures, a water pump receiving from said reservoir and having a forwardly directed discharge mouth discharging into said tub at the 20 rear lower part of the same and means for operating said pump.

6. A washing machine having in combination a tub, a pump having a forwardly directed discharge mouth running into the lower rear part 25 of the tub and directing fluid along the bottom of the tub and upwardly along the front of the tub, a rearwardly extending deflector at the upper part of the front of the tub directing the fluid rearwardly, the upper edges of all but the 30 front of the tub being inwardly curved adjacent the level of the deflector and the curved portions having a multiplicity of horizontally spaced drain apertures therein, certain of said apertures being located at lower levels than others 35 and a reservoir for catching the fluid draining through said apertures, said pump having an inlet receiving from said reservoir.

7. A washing machine comprising a tub having the general shape of the bowl of an ordinary 40 clay smoking pipe, the upper part of the front of the tub having a rearwardly extending water deflector joining the same and the remainder of the upper part of the tub being inwardly curved adjacent the level of said deflector, the 45 curved portion being provided with a multiplicity of circumferentially spaced drain apertures located certain of them at different levels close to but somewhat below the level of said deflector, a reservoir receiving from said drain apertures 50 a water pump receiving from said reservoir and having a forwardly directed discharge mouth running through the lower part of the rear of the tub and means for operating said pump.

8. A washing machine comprising a tub having an enclosing wall and a bottom inclining generally upwardly and forwardly from the rear of the tub and merging into the front and sides of the wall, the front of the tub having a rearwardly extending top section forming a water 60 deflector and the remainder of the tub being inwardly curved at its top adjacent the level of said deflector and the curved portion having a multiplicity of circumferentially spaced drain apertures therein located certain of them at different levels close to but somewhat below the level of said deflector, a reservoir receiving from said drain apertures, a water pump receiving from said reservoir and having a forwardly directed discharge mouth discharging into said 65 tub at the lower rear part of the same and means for operating said pump.

9. A washing machine comprising a tub of general circular-shape in top plan view, of general semi-circular shape in transverse vertical cross 70

- section, and of general upwardly and forwardly flaring funnel-shape in central longitudinal vertical cross section, a water deflector joining and extending rearwardly from the front upper part 5 of the tub, the sides and rear upper parts of the tub being continuously curved inwardly to form a curved portion at a level approximately flush with said deflector, said curved portion being provided with a multiplicity of drain apertures located at numerous circumferentially spaced points, a reservoir receiving from said drain apertures, a water pump receiving from said reservoir and having a discharge mouth running through the rear of said tub near the bottom 10 of the tub and directed toward the front of the tub and means for operating said pump.
10. In a washing machine, a tub having a rearwardly extending deflector joining the upper portion of its front and having the upper portion of the remainder of the tub inwardly curved adjacent the level of said deflector, the inwardly curved portion having a multiplicity of horizontally spaced drain apertures therein, means 15
- 20

for circulating washing fluid upwardly along the front of the tub to strike said deflector and means for catching the fluid draining through said apertures and supplying said circulating means with the drained washing fluid.

11. A washing machine comprising a tub having a bottom inclining upwardly and forwardly from the rear of the tub, the upper part of the front of the tub having a rearwardly extending water deflector joining the same and the upper 10 part of the remainder of the tub being inwardly curved adjacent the level of said deflector and the curved portion having a multiplicity of circumferentially spaced drain apertures therein located close to but somewhat below the level 15 of said deflector, a reservoir surrounding at least a portion of said tub and receiving from said drain apertures, a water pump receiving from said reservoir and having a forwardly directed discharge mouth discharging into said tub at the 20 rear lower part of the same and means for operating said pump.

CARL J. SODERHOLM.
